M. H. DETTE.

CUTTER HEAD.

APPLICATION FILED SEPT. 14, 1907.

920,549.

Patented May 4, 1909.

UNITED STATES PATENT OFFICE.

MAX HENRY DETTE, OF WOODCLIFF, NEW JERSEY, ASSIGNOR TO ALBERT PRYIBIL, OF NEW YORK, N. Y.

CUTTER-HEAD.

No. 920,549.

Specification of Letters Patent.

Patented May 4, 1909.

Application filed September 14, 1907. Serial No. 892,885.

To all whom it may concern:

Be it known that I, MAX HENRY DETTE, a citizen of the United States, residing at Woodcliff, Hudson county, and State of New Jersey, have invented certain new and useful Improvements in Cutter-Heads, of which the following is a specification.

My improvements relate to rotary cutter heads generally, and particularly for those used in automatic feed planers, hand feed planers, molding machines and the like, in which a relatively high speed of rotation is essential,—resulting in a centrifugal force which has heretofore been a great source of danger and disaster.

My object is not only to counteract this centrifugal force but also to utilize it as an element of safety,—the design being to afford an absolutely secure, simple, durable, cheap, perfectly balanced, structure adapted to all the requirements of practical use.

The invention consists in the specific construction and arrangement of parts herein-after described and claimed.

25 In the accompanying drawings, Figure 1, is an elevation of a cutter head embodying my invention; Fig. 2, a transverse section upon a larger scale taken upon line 2—2—Fig. 1; Fig. 3, is a similar view taken on plane of line 3—3—Fig. 1; Fig. 4, is a similar view taken upon plane of line 4—4—Fig. 1; Fig. 5, is an elevation of a portion of the clamping bar.

A, is a solid cutter head made in one piece. 35 It may be made integral with the shaft or bored centrally and mounted on the latter as is customary in the case of short interchangeable cutter heads. In either case the essential feature is a one piece solid head in 40 which the tool and clamp bar seats are directly formed. These seats consist of longitudinal grooves a , a , accurately milled out and parallel to each other and to the longitudinal axis of the head. Two of these 45 grooves are shown in the drawings, although any plural number may be formed in a head of suitable diameter, provided they are equidistant, so as to preserve the accurate balance of the head. The outer side wall of 50 each groove constitutes a seat or abutment a' , for the support of a cutter blade c . The inner surface of this abutment a' , is preferably in a plane parallel, or substantially parallel to a plane passing through the longitudinal axis of the head. Gage screws g , 55 engaging with the head, project into each

groove a , at its inner or deeper portion, and form adjustable rests for the inner edge of the cutter blade c , as will be understood by reference to Fig. 3. The latter is held in position against the abutment a' , by a clamping bar d , in the groove a , said clamping bar d , being pressed against the blade c , by means of a series of binding screws d' , d' , tapped into the head in positions at right angles to the inner surface of the abutment a' , as shown in Fig. 2. Upon reference to Figs. 2, 3 and 4, it will be noted that the clamping bars d are offset at different points to correspond with the similar offsets in the cutter head A whereby I attain increased bearing surfaces and greater strain resisting bearings for the clamping bars in the head so that when the clamping bars are in position, as seen in said views, they are securely held against lateral displacement as well as outward accidental movement whereby they are more rigidly retained in their affixed positions.

The cutter head A, is recessed at a^2 , a^2 , and a^3 , a^3 , so that the outer ends of both the set screws g , and of the binding screws d' , d' , may be countersunk below the circular periphery of said cutter head,—while rendering them still accessible for purposes of manipulation.

The edge of each groove a , opposed to the abutment a' , (what may be designated as the inner edge) is formed with a shoulder a^4 , for engagement with the edge or shoulder d^2 , on the clamping bar d , for the purpose of retaining the latter in place and counteracting the effects of centrifugal force when the cutter head is in use.

In assembling the parts the clamping bars d , are first inserted in the grooves a , and then the cutting blades are inserted. After the cutting edges have been accurately set to an external gage by means of the set screws g , the cutter blades c are locked in such position by means of the binding screws d' , which press the said blades rigidly against abutments a' . It must be noted in this connection that the backs of the cutting blades rest against the abutments a' , so that the strain of cutting as well as of centrifugal force in use is directed against said abutments and not against the clamping bars d , and screws d' . By this arrangement also the centrifugal thrust of the clamping bars is against the cutting blades and away from the clamping screws; while the said clamping bars d , are

locked in position and reinforced against all possibility of centrifugal displacement by the shoulders a' .

It will be seen that my cutter is very simple and substantial in structure while at the same time it is comparatively inexpensive. The cutting blades being backed and reinforced by the solid head which bears all the strain in use, and centrifugal force being utilized to retain the parts in place all danger from high speed of rotation is practically eliminated. It will also be seen that the cutting head is perfectly balanced since the parts are evenly distributed and permanently fixed with relation to the axis of rotation,—the clamping bars d , particularly being held in prescribed, unvarying positions, with relation to the axis of rotation so that the perfect alinement of the cutter head as a whole is insured, owing to the absence of any tendency to eccentricity. The clamping bars extending the whole length of the cutting blades, distributes the pressure evenly over the whole of the latter and by counterbalancing the elasticity of the metal and preventing buckling or curvature of the blades between the binding screws insure cutting edges which are in perfect alinement longitudinally and absolutely parallel with relation to each other and the central axis of the head. They also compensate for any variation in pressure longitudinally exerted by the several binding screws. Furthermore the pressure exerted by the clamping bars d , and screws d' , against the cutter blades is at right angles to the latter and diametrically opposed to the supporting surfaces of the abutments a' , so that during the operation of clamping the blades in position there is no tendency to distribute their set or alinement. By this arrangement, also, as before intimated the clamping screws d' , are relieved of the strain of work which is

thrown directly against and upon the solid one piece cutting head. To summarize by my construction of cutter head, I attain simplicity, cheapness, strength, durability, rectangular pressure, the counterbalancing and utilization of centrifugal force and absolute safety in use.

What I claim as my invention and desire to secure by Letters Patent is,

The improved cutter head herein described comprising a solid head in one integral piece formed with tool and clamp bar seats consisting of longitudinal grooves milled out parallel to each other and to the longitudinal axis of the head, the outer side wall of each groove constituting an abutment for the support of a cutter blade, the inner surface of said abutment being parallel to a plane passing through the longitudinal axis of the head, said head being recessed at diametrically opposite points and upon diametrically opposite sides, said grooves being offset at different points and in different planes, the edge of each groove opposite the blade seat being formed with an offset and shoulder, combined with blades, clamp bars offset at different points in different planes and seated in said grooves and formed with shoulders engaging the shoulders of the grooves, set screws adjustably mounted in the head and bearing against the rear edges of the blades, and binding screws adjustable in the head at right angles to the set screws and bearing against the clamping bars adjacent said shoulders and pressing the clamping bars against the blades, the heads of said set screws and binding screws being disposed in said recesses and readily endwise accessible.

MAX HENRY DETTE.
